GARRETT ERKSON, OF BROOKLYN, NEW YORK, ASSIGNOR TO RALPH H. ISHAM.

Design No. 3,035, dated May 12, 1868.

DESIGN FOR A MEDALLION.

The Schedule referred to in these Letters Patent and making part of the same.

TO ALL WHOM IT MAY CONCERN:

Be it known that I, GARRETT ERKSON, (assignor to Ralph H. Isham,) of Brooklyn, in the county of Kings, and State of New York, have originated and produced a new and original Design for a Medallion of Valentine Mott, M. D., of which the following is a full, clear, and correct description, reference being had to the accompanying photographic copies of the medallion, making a part of this specification.

In the medallion, a side or profile view of the late Dr. Valentine Mott is presented, as clearly shown in the photographic impressions of the same sent herewith, and shown.

What I claim as my invention, and desire to secure by Letters Patent, is—

The design for a medallion of Valentine Mott, herein set forth.

GARRETT ERKSON.
